UNITED STATES PATENT OFFICE.

JOSEPH BUCHALTER, OF NEW YORK, N. Y.

CANE FRAME FOR CAPS AND HATS.

1,077,796.

Specification of Letters Patent.

Patented Nov. 4, 1913.

Application filed September 28, 1912. Serial No. 722,936.

To all whom it may concern:

Be it known that I, JOSEPH BUCHALTER, a subject of the Emperor of Austria-Hungary, and a resident of the city of New York, borough of Manhattan, in the county and State of New York, have invented a new and Improved Cane Frame for Caps and Hats, of which the following is a full, clear, and exact description.

10 The object of the invention is to provide a new and improved cane frame for caps, hats and similar articles of head gear and arranged to render the article exceedingly light, to insure comfort to the wearer, to 15 reinforce the article, and to render the same flexible with a view to permanently maintain the original shape of the article even if roughly used.

For the purpose mentioned use is made 20 of a cane frame having a side and a top, of which the latter is united with the upper edge of the side, and the said frame supports the sides and top of the body of the cap, hat or similar article.

25 A practical embodiment of the invention is represented in the accompanying drawings forming a part of this specification, in which similar characters of reference indicate corresponding parts in all the views.

30 Figure 1 is a perspective view of a uniform cap provided with the improved cane frame, part of the cap body being broken out; Fig. 2 is an enlarged cross section of part of the same; Fig. 3 is a similar view of 35 the same provided with a lining intermediate the cap body and the cane frame; Fig. 4 is a sectional plan view of the joint between the parts of the upper side section of the cane frame; Fig. 5 is a perspective 40 view of a uniform cap provided with a cane frame having a lower or basal band of relatively stiff material and an upper band of relatively light material, part of the cap body being broken out; and Fig. 6 is an enlarged cross section of part of the same.

45 As shown in Figs. 1 and 2, the body A of the cap is provided with a vizor B and with the usual sweatband C, and within the body A is arranged a reinforcing frame D, 50 of split cane or ratan, made of strips interwoven with each other to form an open mesh fabric, as indicated in the drawings. The reinforcing frame D consists of a top D' and a side made in sections D², D³, of 55 which the lower section D³ is preferably vertically disposed while the upper section

D² is inclined upwardly and outwardly so as to follow the shape of the cap body A, which latter is provided with the usual top A', the upper side section A² and the lower side section A³ stretched over the corresponding parts of the frame D. In practice, the top D' of the cane frame D is made of a single piece, and the upper edge of the upper section D² of the side of the cane frame is provided with a binding E and a similar binding F is arranged on the overlapping edge of the top D', the two bindings E and F being sewed or otherwise fastened together so as to securely unite the top D' with the upper edge of the upper section D². The lower edge of the upper section D² is provided with a binding G and a similar binding H is arranged on the upper edge of the lower section D³, and the said bindings G and H are fastened together by stitches or other means to securely unite the upper and lower sections D², D³ with each other. The binding H is extended downward intermediate the cap section A³ and the frame section D³ to form a lining H' for the cap section A³ and the lower end H² of the said lining H' and the lower portion A⁴ of the side A³ of the cap body are turned under at the lower end of the cane frame side section D³, and the turned under portion as well as the lower edge of the sweatband C are fastened together by stitches to unite the several parts. The bindings F and G are preferably reinforced by wires F², G' formed into ring shape to conform to the shape of the cap.

90 The upper side section D² of the cane frame D is preferably made of two parts or strips of a woven cane or ratan fabric, and the parts are overlapped at their ends and fastened together by a vertical binding I, as plainly indicated in Figs. 1 and 4. The lower section D³ is preferably made of one piece with the ends overlapping and sewed together. The top D' and the upper side section D² of the cane frame are formed of strips interwoven to provide a large mesh, while the lower section D³ may be made of strips closely interwoven so as to be somewhat stiffer than the upper section D² (see Figs. 5 and 6).

100 Caps for winter wear are preferably provided with a lining (see Fig. 3), of which a portion J is interposed between the top D' of the cane frame and the top A' of the cap body, another double portion J' is interposed

between the upper side section D^2 of the cane frame and the upper side portion A^2 of the cap body, and a part J^2 of the double portion J' is extended downward and interposed between the lower side section D^3 and the cap section A^3 to take the place of the lining H' previously mentioned. A lining H^4 engages the lower end of the section D^3 . The several parts are united by stitches at the joints to insure the formation of a cap reinforced with a cane frame, which is exceedingly light to insure comfort to the wearer, and is sufficiently strong and flexible to reinforce the cap body with a view to maintain the original shape thereof.

Having thus described my invention, I claim as new and desire to secure by Letters Patent:

1. A cap or the like, comprising a cap body and a reinforcing frame over which the said body is stretched, the body being made of a textile fabric and the reinforcing frame being made of cane, the reinforcing frame comprising a top provided with an overlap-

ping edge having a binding, and a crown 25 frame provided at its upper edge with a binding fitting against the said top edge binding, and fastening means for fastening the said bindings together.

2. A cap or the like, comprising a cap 30 body and a reinforcing frame over which the said body is stretched, the cap body being made of a textile fabric and having a top and an annular side connected with the top, the said reinforcing frame being made of 35 cane and comprising a top and a side made in upper and lower sections, and a lining interposed between the lower section of the said cane frame side and the lower portion of the said cap body side. 40

In testimony whereof I have signed my name to this specification, in the presence of two subscribing witnesses.

JOSEPH X BUCHALTER.
